CONTROL APPARATUS

Theodore A. Cohen, Chicago, Ill., assignor, by
mesne assignments, to Wheeleo Instruments
Company, Chicago, Ill., a corporation of Illinois

Application December 31, 1942, Serial No. 470,916

18 Claims. (Cl. 205—16)

This invention relates to control apparatus and more particularly to a control apparatus for automatically stopping a wire drawing apparatus upon any defect or breakage of the wire being drawn.

One of the objects of my invention is to provide an apparatus for efficiently controlling a wire drawing apparatus to sharply and effectively stop the same in event of the aforementioned contingency, energize alarms, and to provide an improved apparatus whereby a minute change in an impedance change device may control an oscillator circuit to effect such control.

Other and further objects of my invention will be apparent as the same becomes better understood from an examination of the specification and claims in conjunction with the accompanying drawings wherein:

Figure 1 represents a diagrammatic and schematic view of an apparatus embodying my invention;

Figure 2 is a perspective view of the mounting and housing containing the apparatus of Figure 1;

Figure 3 is a view similar to Figure 2 showing a portion of the impedance change device housing cut away and the side of the oscillator circuit housing removed to show the manner of mounting said device and circuit in their respective housings;

Figure 4 is a view similar to Figure 3 of a modified form of the mounting and housing for the apparatus;

Figure 5 is a detail fragmentary side elevational view of the mounting and housing for the impedance change device of the apparatus.

Referring to the drawings more particularly, reference character 1 designates a drum of wire 2 to be drawn from a larger diameter to a smaller diameter. Wire 2 is adapted to be unwound from said drum 1 and drawn over a roller 3, through a die 4, through an impedance change device 5 hereinafter described, and over a roller 6 to a drum 7 which is driven by an electric motor 8. The motor 8 has a solenoid 9 the winding of which is in parallel with the motor operating winding (not shown) and both are connected to a source of current 10 through a switch 11, controlled by a relay 12 in the output circuit of the oscillator circuit 13 hereinafter described. Thus when the power supply to the motor 8 is cut off, the solenoid releases a brake arm permitting a spring 15 to apply a brake 16 to the drum 7. Likewise operation of relay 12 also causes switch 11 to make contact 64 to en-

ergize alarm pilot light 65 when the wire breaks.

The impedance change device 5 comprises a housing 17, mounted as will be hereinafter described, provided with aligned openings 18 and 19 in opposite vertical walls for the wire 2. Within housing 17 there is mounted an oscillating circuit including an inductance or coil 20 which surrounds the wire 2 and is in the nature of a variable inductance or impedance change device 10 whose inductance varies with the condition of said wire whereby any radical change therein such as breakage thereof will cause a substantial change in said inductance of coil 20. This impedance change device is adapted to control the oscillator circuit 13 as will be hereinafter described.

A grid tank circuit is mounted in the container 17. The details of mounting will be hereinafter described in conjunction with Figures 2 to 5 inclusive.

A conductor 21 connects one end of coil 20 to a coupling condenser 22 and the latter is connected to a male terminal plug 23 on container 17. The other end of the coil 20 is connected to another male terminal plug 24 on the container 17.

The male plugs 23 and 24 are adapted to connect with female connector elements 25 and 26, respectively, at one end of a concentric conductor cable 27 insulated from ground by an external rubber sheath or cover (not shown). The cable 27 comprises an inner conductor 28, separators 29 and an outer conducting sheath 30. The end of the cable opposite to the connector 23—26 is provided with a connector similar thereto for connection to the input of an oscillator circuit hereinafter described.

The concentric co-axial conductor cable is constructed in well known manner with a core conductor fixedly and concentrically positioned within a conducting sheath which may be covered with insulation (not shown). By properly choosing the values of the capacitive and inductive components of the oscillating circuit in enclosure 17, the cable is properly terminated so that minimum radio frequency loss is obtained in the system due to the cable for any substantial length thereof. In this manner the remote control assembly just described may control an oscillator apparatus hereinafter described without fear of transmission losses which otherwise would reduce the sensitivity of the apparatus if not actually prevent its operation.

The oscillator circuit includes a vacuum tube 35 connected to a plate tank comprising an in-

ductance 40, variable condenser 41 for tuning to resonance, as will hereinafter be described, and grid bias resistor or grid leak 52 for said tube.

Alternating current voltages are obtained from a multi-winding transformer having a primary winding 44, connected to a suitable source of alternating current 10, and having a plurality of secondary windings 46, 55, 56 and 57 arranged to supply suitable voltages to the tube circuits. The tube 35 and repeater tube 47, hereinafter described, are self rectifying and therefore the operation will be described only with respect to the positive half cycles of the alternating current voltages.

The output section of the tube 35 may be traced from the left-hand terminal of the secondary winding 46 through the plate tank circuit 40, 41, the anode or plate 31, the cathode 38, the secondary winding 56, conductor 56a, a load impedance or resistor 53 and thence to the right hand terminal of secondary winding 46. By-pass condensers 42 and 54 are connected as shown and prevent the flow of high frequency oscillatory currents through the transformer windings and through the load impedance 53. The total voltage impressed across the anode circuit of tube 35 is the sum of the voltages of the secondary windings 46 and 56.

The output circuit for the repeater or amplifier tube 47 may be traced from the left hand terminal of the secondary winding 55 to the anode or plate 49, the cathode 50, the secondary winding 56, the voltage of which is in phase with the voltage of the winding 55, the operating winding 12 of the relay 58 and to the right hand terminal of the winding 55. A condenser 61 is connected as shown across the relay winding 59 and prevents chatter of relay by supplying energy to relay during negative or non-conducting portion of A. C. cycle. Transformer secondary winding 57 is connected to filaments 39 and 51 to heat cathodes 38 and 50, respectively, by wires X-X not completed. The grid bias for effecting proper operation of the repeater tube 47 is obtained by connecting the grid or control electrode 48 to one end of the load resistor 53, the remaining portion of this circuit extending from the cathode 50 to the secondary transformer winding 56, the conductor 56a to the opposite end of the load resistor 53. It will be apparent that the voltage across the winding 56 is opposite to and thus compensates for a portion of the voltage drop across the load impedance 53 and accordingly when the oscillator tube 35 is in oscillatory condition so that a plate current of low value flows through the load impedance 53. A minimum negative bias equal to the difference between the voltage of the winding 56 and the voltage drop across the load impedance is impressed on the grid 48. Under these conditions, and with proper voltages, the tube constants, and the value of the load resistance all so pre-chosen to provide a low negative grid bias, a high repeater plate current is obtained for proper operation of the relay.

A regenerative coupling is provided between the grid circuit of the tube 35 and the output of the repeater tube 47, as shown. The grid circuit for the oscillator tube 35 extends from the cathode 38, the transformer winding 56, the lower end of relay winding 12, the tap 60 and the grid bias resistor or grid leak 52 to the grid 36.

A fixed grid bias is applied, by the above circuit, to the grid 36 which is equal to the voltage drop across the relay winding 59 to tap 60 and is

so chosen that with maximum current flowing in the output circuit of the amplifier or repeater tube 47 the maximum desired negative bias is applied to the grid 36.

5 The plate tank is tuned to predetermined resonance with condenser 41 so as to close relay 12 when wire 2 is at desired normal reduced condition. Should the wire 2 change from desired condition such as breaking, the inductance of coil 10 20 changes, causing eventual opening of relay 12 and switch 11 to stop driving motor 8 and apply brake 16 to drum 7.

When wire 2 breaks as it invariably will, if at all, beyond the die 4, changing inductance of coil 15 20, the oscillator circuit is detuned, causing its plate current to rise sharply, increasing the voltage drop across the resistor 53, which correspondingly increases the negative bias upon the amplifier tube 47 with a consequent drop in its plate 20 current through the relay 59. The decrease in current through the relay 59 causes a decrease in the negative grid bias applied to the grid of the oscillator tube 35, which tends to further increase the plate current of the oscillator tube 35. 25 This increase in the oscillator plate current further increases the voltage drop across the load resistor 53 and the negative bias upon the amplifier tube 47 with the consequent effect of rapidly dropping the amplifier plate current to the 30 cut-off point, which causes approximately zero level in plate current and opening of relay 12 to stop motor 8 and apply brake 16. When wire 2 is rethreaded and restored the reverse occurs. Circuit is retuned and oscillator plate current 35 drops, decreasing the drop across resistor 53, which decreases the negative bias on the amplifier tube 47; the plate current of the amplifier increases, increasing the drop across the relay 53, which increases the negative bias on the grid of 40 the oscillator 35, aiding in dropping the oscillator plate current, which further tends to decrease the bias upon the amplifier 47, etc., with the result that the final positioning of the plate current of amplifier 47 is at saturation. By the judicious 45 choosing of load resistance 53, of the resistance of the relay winding 59 and the proper apportioning of bias voltages as shown, the values of plate current between cut-off and saturation may be fixed at any desired value. The result is that 50 large, abrupt, and rapid plate current changes are always obtained. The result obtainable is comparable to the triggering off of a "Thyratron" type hot cathode grid control rectifier without the necessity of using gas-filled tubes.

55 Study of the circuit arrangement will also bring out that the system is self compensating for changes in line voltage which prevents shiftage of the control point if the line voltage should change.

60 It is not necessary that the apparatus be limited to the use of separate vacuum tubes, each containing separate triode elements, since these separate tubes have been chosen only as a matter of convenience. Dual purpose tubes having triode 65 elements in a common envelope may be operated in the same manner. Direct current voltages may also be used.

It will be noted that the plate supply for tubes 35 and 47 are obtained from winding 46 and 55, respectively, in series with 56. Should the line voltage fall the supply voltage from 55 would reduce and therefore the plate current flow in plate circuit of tube 47 would tend to decrease. However, since winding 46 supplies the plate circuit 70 of tube 35 and since the negative bias on grid 48

is obtained from drop across resistor 53 due to plate current flow in plate circuit of tube 35, the plate current of tube 35 is also reduced with reduction of voltage from 46. Therefore negative bias on grid 48 is reduced keeping the plate current flow in plate circuit of tube 47 substantially constant. The reverse result is obtained with rise in line voltage. This self compensating feature is important in electronic control apparatus since it prevents shift of the control point or level upon changes in line voltage. Aging of tubes is also compensated for in the same manner in conjunction with the regenerative connection between tap 60 and resistor 52.

In summary, the advantages of this circuit are manifest, inasmuch as a relay with a high throw-out percentage is not necessary, since the plate current changes through said relay are very rapid and very large. It is impossible to lose control of the oscillator, since, because of the fact that it is self-rectified, oscillations, no matter how minute, will always reoccur. Other variations of this circuit will readily occur to those versed in the art, such as the use of a common power supply, with a self-rectified circuit, instead of separate voltages as shown. Such circuits have been designed and are entirely feasible. The one shown being one of a family of such circuits and being chosen as the most descriptive of the above-explained operation.

Referring to Figures 2 and 3, reference character 100 designates a pedestal having base and upper flanges 101 and 102, respectively. Bolted to the upper flange 102 is an upper pedestal section flange 103 of upper pedestal section 104.

Section 104 supports a housing 105 for the oscillator circuit 13 which is substantially vapor and moisture proof. The parts of said circuit as set forth in Figure 1 and the description thereof are mounted in said housing 105 in suitable manner. The housing 105 has an upper extension 17a which contains the aligned openings 18 and 19 for the wire 2 and also contains the coil 20 aligned with said openings and the condenser 22 cooperating to form the grid tank oscillating circuit, said grid tank forming a self contained unit in said housing extension 17a.

In Figures 4 and 5 the housing for the self contained grid tank unit is designated 17, has the grid tank terminal 23-26 as described in connection with Figure 1 and the concentric conductor cable 27 connected as previously described to the oscillator circuit 13 in the housing 105a therefor. In this embodiment the housing 17 together with its self contained impedance change device therein are vertically adjustable relative to the oscillator 13. The housing 105a of said oscillator 13 has a vertical stem 106 mounted to extend upwardly from said housing. A slidable bracket 107 and lock screw 108 is attached to the back of housing 17 for holding the same in desired vertical position on stem 106 so that the aligned openings 18 and 19 may be aligned on essentially the same level as the axis of the wire being drawn.

As shown in Figures 3 and 4 the external adjustment for tuning to resonance of the condenser 41 of Figure 1, is at 41a.

The advantages of the aforescribed apparatus will be apparent without further detail.

I am aware that many changes may be made without departing from the principles of my invention and I therefore do not wish to be limited to the details shown or described.

I claim:

1. The combination with a machine tool pro-

vided with means for feeding the work thereto, of a work responsive impedance change device in proximity to said work, an oscillator circuit spaced a substantial distance from said device away from said work, an oscillating circuit mechanically mounted in proximity to said device and operatively connected thereto for control thereby, a concentric conductor cable having its central conductor and shield connected between terminals of said second circuit and the grid circuit of said first circuit and means controlled by said oscillator circuit for stopping the feed means when the work departs from predetermined conditions.

15 2. The combination with a machine tool provided with means for feeding the work thereto, of a work responsive impedance change device in proximity to said work, an oscillator circuit, an oscillating circuit mechanically mounted in proximity to said device and operatively connected thereto for control thereby, a concentric conductor cable having its central conductor and shield connected between terminals of said second circuit and the grid circuit of said first circuit, said oscillating circuit adapted to be tuned to predetermined resonance with the oscillator plate circuit and adapted to change the tuning of the latter upon a change of impedance of said device and means controlled by said oscillator circuit for stopping the feed means when the work departs from predetermined conditions.

20 3. The combination with a machine tool provided with means for feeding the work thereto of a work responsive impedance change device in proximity to said work, an oscillator circuit provided with grid and plate tanks and spaced a substantial distance from said device away from said work, the grid tank being mechanically mounted in proximity to said device and operatively connected thereto for control thereby, a concentric conductor cable having its central conductor and sheath connected between terminals of said grid tank and the grid circuit of said oscillator circuit and means controlled by said oscillator circuit for stopping the feed means when the work departs from predetermined conditions.

25 4. The combination with a machine tool provided with means for feeding the work thereto of a work responsive impedance change device in proximity to said work, an oscillator circuit provided with a plurality of tanks and spaced, except for one of said tanks, a substantial distance from said device away from said work, one of said tanks being mounted in proximity to said device and operatively connected thereto for control thereby, and a concentric conductor cable having its central conductor and sheath connected between terminals of said one tank and the rest of said oscillator circuit whereby the same may be controlled in accordance with predetermined conditions of said work.

30 5. In a control system for controlling the operation of a machine tool upon work, the combination of a vacuum tube oscillator having input and output circuits, a load impedance effectively included in said output circuit, a vacuum tube repeater having an input circuit coupled to said load impedance to control the output circuit of said repeater in accordance with changes in the voltage across said load impedance, an electro-responsive device having an operating winding effectively included in said repeater output circuit and a work responsive device for affecting 35 the tuning of said oscillator circuit to vary the

voltage across said load impedance whereupon said repeater causes operation of said electro-responsive device for controlling the operation of said tool.

6. In a control system for controlling the operation of a machine tool upon work, the combination of a vacuum tube oscillator having tuned input and output circuits, a load impedance effectively included in said output circuit adapted to be traversed only by the nonpulsating component of the current in said output circuit, a vacuum tube repeater having an input circuit coupled to said load impedance for energization in accordance with the voltage across said impedance, a repeater output circuit, an electro-responsive device connected to said repeater output circuit, and means responsive to the condition of the work being operated on by said tool to be controlled by operation of said electro-responsive device including a portion of said oscillator input circuit spaced from the rest of said oscillator circuit, and connected thereto by a coaxial conductor cable, for changing the tuning of said oscillator to thereby vary the voltage across said load impedance to effect operation of said electro-responsive device and thereby control operation of the machine tool.

7. In a machine tool control system, the combination of an electron discharge device, having input and output circuits adapted to be tuned to predetermined resonance to cause said device to operate as an oscillator, a load impedance effectively included in said output circuit so as to be traversed only by the non-pulsating component of the oscillator output current, whereby the voltage across said impedance changes when the oscillatory condition of said tube varies from said resonance, a repeater tube having input and output circuits, a source of biasing potential, means connecting said load impedance and said source in series relation to said repeater input circuit with the voltage of said source in opposition to and of less magnitude than the voltage when said oscillator is in said resonant condition, an electro-responsive device having an operating winding effectively included in said repeater output circuit for controlling the operation of said machine tool in response to variations in the energization of said winding and work piece responsive means connected to the oscillator circuit by a fixed impedance conductor to control the tuning of said oscillator circuit in accordance with physical changes in said work piece, whereby the bias voltage impressed on said repeater input circuit varies from a desired minimum during resonant conditions to a desired maximum upon a physical change in the work piece to cause a cessation of oscillations, said variation in the bias voltage controlling the output of said repeater tube to operate said electro-responsive device in accordance with a physical change in said work.

8. In a machine tool control system, the combination of a vacuum tube oscillator having tuned input and output circuits, a load impedance effectively included in said output circuit adapted to be traversed only by the nonpulsating component of the current in said output circuit, a vacuum tube repeater having an input circuit, coupled to said load impedance for energization in accordance with the voltage drop across said impedance, a repeater output circuit, a relay having an operating winding connected in said repeater output circuit, and means responsive to

the condition of said work including a variable impedance device in a portion of said oscillator input circuit to change the tuning of said oscillator, whereby the voltage drop across said load impedance is varied to effect operation of said relay to control a machine tool apparatus.

9. In a machine tool control system, the combination of an oscillator circuit including input and output circuits coupled with the input and output electrodes of an electron discharge device, means including a variable impedance device responsive to the condition of work on said tool in a portion of said oscillator circuit to change the tuning thereof, a load impedance effectively included in said output circuit so as to be traversed only by the non-pulsating component of the output current, an amplifier circuit including input and output circuits coupled with the input and output electrodes of a second electron discharge device, said amplifier input circuit being so coupled with said load impedance as to vary the amplifier output current in accordance with changes in the voltage across said load impedance, and an electro-responsive device controlled by said amplifier output current for controlling said machine tool in accordance with change in the condition of the work.

10. In combination, a vacuum tube oscillator having tuned input and output circuits and provided also with means responsive to the condition of work in a machine tool for changing the tuning of said circuits, a load impedance effectively included in said output circuit, a vacuum tube repeater having an input circuit coupled for energization in accordance with the voltage across said load impedance, whereby changes in the tuning of said oscillator are effective to control said repeater, an output circuit for said repeater, and a regenerative coupling between said repeater output circuit and said oscillator input circuit for effecting a sharp variation of the repeater output current between saturation and cut-off in response to a change in the tuning of said oscillator independently of the magnitude of said change.

11. In a machine tool control system, the combination of an oscillator circuit including input and output circuits coupled with the input and output electrodes of an electron discharge device, an impedance change device responsive to the condition of the work on said tool in a portion of said oscillator circuit to change the tuning thereof, an amplifier circuit including input and output circuits coupled with the input and output electrodes of a second electron discharge device, means coupling said amplifier input circuit with said oscillator output circuit whereby a change in the tuning of said oscillator circuit effects a change in the output current of said amplifier an electro-responsive device having an operating winding adapted to operate said device between two positions upon changes of predetermined magnitude in said amplifier output current, and a regenerative coupling between said winding in said amplifier output circuit and said oscillator input circuit for effecting a sharp variation of said amplifier output current between cut-off and saturation in response to an initial change in the tuning of said oscillator of sufficient magnitude to effect a slight change in said amplifier output current, whereby said electro-responsive device is quickly operated between said two positions in response to a critical change of said impedance device regardless of the magnitude of said change.

12. In a machine tool control system, the combination of an electron discharge device or tube having input and output circuits adapted to be tuned to predetermined resonance to cause said tube to operate as an oscillator, a load impedance effectively included in said output circuit so as to be traversed only by the non-pulsating component of the oscillator output current, whereby the voltage across said impedance changes when the oscillatory condition of said tube varies from or toward resonance, a repeater tube having input and output circuits, a source of biasing potential, means connecting said load impedance and said source in series relation to said repeater input circuit with the voltage when said oscillator is in resonant condition, an electro-responsive device having an operating winding effectively included in said repeater output circuit for controlling the operation of said machine tool in response to variations in the energization of said winding and work piece responsive means connected to the oscillator circuit to control the tuning of said oscillator circuit in accordance with physical changes in said work piece, whereby the bias voltage impressed on said repeater input circuit varies from a desired minimum during resonant conditions to desired maximum upon a physical change in the work piece to cause a cessation of oscillations, said variation in the bias voltage controlling the output of said repeater tube to operate said electro-responsive device in accordance with a physical change in said work to thereby control a machine tool accordingly.

13. The combination with a wire drawing die and means for drawing wire therethrough, of a wire responsive impedance change device including an inductive coil surrounding said wire after it leaves said die, an oscillator circuit spaced a substantial distance from said device away from said wire and oscillating circuit mechanism mounted in proximity to said device and operatively connected thereto for control thereby, a concentric conductor cable having its central conductor and shield connected between terminals of said second circuit and the grid circuit of said first circuit and means controlled by said oscillator circuit for stopping said first means in the event of breakage of said wire.

14. In a control system for controlling the operation of a wire drawing apparatus, the combination of a vacuum tube oscillator having input and output circuits, a load impedance effectively included in said output circuit, a vacuum tube repeater having an input circuit coupled to said load impedance to control the tube circuit of said repeater in accordance with changes in the voltage across said load impedance, an electro responsive device having an operating winding effectively included in said repeater output circuit and a device including an inductive coil surrounding the wire being drawn for affecting the tuning of said oscillator circuit to vary the voltage across said load impedance whereupon said repeater causes operation of said electro responsive device for stopping the operation of said apparatus upon the breakage of the wire.

15. In combination, a vacuum tube oscillator having tuned input and output circuits and provided also with means including an inductive coil

surrounding and responsive to the condition of the wire being drawn in a wire drawing apparatus for changing the tuning of said circuits, a load impedance effectively included in said output circuit, a vacuum tube repeater having an input circuit coupling for energization in accordance with the voltage across said load impedance whereby changes in the tuning of said oscillator are effective to control said repeater, an output circuit for said repeater and a regenerative coupling between said repeater output circuit and said oscillator input circuit for effecting a sharp variation of the repeater output current between saturation and cut-off in response to a change in the tuning of said oscillator independently of the magnitude of said change.

16. The combination with a wire drawing apparatus provided with means for drawing a wire through a die, of a wire responsive impedance change device including an inductive coil surrounding the wire being drawn, an oscillator circuit provided with a plurality of tanks and spaced, except for one of said tanks, a substantial distance from said device, one of said tanks being mounted in proximity to said device and operatively connected thereto for control thereby, and a concentric conductor cable having its central conductor and sheath connected between terminals of said one tank and the rest of said oscillator circuit whereby the same may be controlled in accordance with predetermined conditions of the wire being drawn.

17. The combination with a wire drawing apparatus provided with means for drawing a wire through a die, of a device responsive to the condition of the wire including an inductive coil surrounding the wire being drawn, an oscillator circuit, a mount for said oscillator circuit including a pedestal situated beneath said wire after the same has left the die, an oscillating circuit including said inductive coil, a vertically adjustable support for said coil and oscillating circuit above said pedestal, a concentric conductor cable having its central conductor and shield connected between terminals of said oscillator and oscillating circuits and means controlled by said oscillator circuit for stopping the wire drawing means upon the breakage of the wire.

18. The combination with a wire drawing apparatus provided with means for drawing wire through a die, of a wire responsive impedance change device including an inductive coil surrounding a wire being drawn and mounted in a suitable housing apertured at opposite ends to receive the wire, an oscillator circuit including a relay mechanism in its output circuit, a housing for said oscillator circuit and relay mechanism, a pedestal support for said housing, an oscillating circuit mounted in the first housing and operatively connected to said inductive coil for control thereby, a concentric conductor cable having its central conductor and shield connected between terminals of said oscillator and oscillating circuits, means for vertically adjusting the position of the first housing relative to the second mentioned housing and means controlled by said relay mechanism for stopping the drawing of the wire in the event said wire should break.
